UNITED STATES PATENT OFFICE.

EGBERT H. GOLD, OF SHELBY, INDIANA.

ATTACHMENT FOR CAR-HEATING SYSTEMS.

SPECIFICATION forming part of Letters Patent No. 768,020, dated August 16, 1904.

Application filed January 9, 1904. Serial No. 188,368. (No model.)

To all whom it may concern:

Be it known that I, EGBERT H. GOLD, a citizen of the United States, residing at Shelby, in the county of Lake and State of Indiana, have 5 invented certain new and useful Improvements in Attachments for Car-Heating Systems, of which the following is a specification.

My invention consists in a new device for controlling the flow of water in filling car- 10 heating systems in which a body of water is contained in a closed circuit and is heated by means in operative contact with said circuit, but not in actual contact therewith.

The object of my invention is to provide an 15 automatically-operating device whereby in filling the radiating-pipes of such a system the water will be caused to travel in one direction, so as to exhaust all air-pockets and force the air out of the pipes in the opposite 20 direction, while at the same time avoiding any possibility of a permanent obstruction to the normal flow through the circulating-pipes of the water when heated. These and such other objects as may hereinafter appear are 25 attained by the device shown in the accompanying drawings, in which—

Figure 1 shows diagrammatically a typical 30 system of piping for a Pullman car. Fig. 2 is a longitudinal section through my improved 35 attachment. Fig. 3 is a cross-sectional view on the line 3 3 of Fig. 2 looking in the direction indicated by the arrows. Fig. 4 is a view on the line 4 4 of Fig. 2 looking in the direction indicated by the arrows, and Fig. 5 is a section on the line 5 5 of Fig. 2.

Like characters of reference indicate the 35 same parts in the several figures of the drawings.

Referring to Fig. 1, 1 indicates the train- 40 pipe, 2 indicates the steam-pipes conducting steam from the train-pipe to the heaters 3 3^a 3^b, 4 indicates a steam-trap of any suitable form, 5 5^a are the expansion-tanks, 6 7 are the coils which are usually located in a Baker 45 heater, (not shown,) 8 indicates the circulating-pipes leading from the coil 6, 9 indicates the circulating-pipes leading from the coil 7, and 10 indicates my filling attachments. Although the piping of cars varies according to 50 differing conditions, the piping shown is typ-

ical, the car being heated by two separate water-circuits 8 9, which are not connected with each other and in which the water may be heated by means of a Baker heater or by means of the steam-heaters, or by both jointly, one 55 set of pipes heating one side of the car and the other set heating the other side of the car. Steam from the train-pipe is conducted through the feed-pipes 2 2 to the heaters 3 3^a 3^b, which are of a familiar type and constitute no part of my present invention, said heaters constituting steam-jackets surrounding the water-pipes, which pass therethrough. Following the circulation in pipes 9, as indicated by the arrows, the water rising through 65 the coils 7 enters expansion-tank 5, thence passes downwardly and then lengthwise of the car, thence beneath the car, where the water-pipe 9 passes through the heater 3, thence upwardly to the end of the car, back, down, 70 and again through the heater 3, again lengthwise of the car, then back again downwardly under a plate and around in a curve or coil in a state-room. Thence returning the pipe passes through the heater 3^a and thence up 75 through the coil 7. In a similar manner the pipes 8, passing across the car, circulate in various loops and coils and return to the coil 6. It will thus be seen that in such a system 80 of piping there are numerous coils and returns in which there is a tendency to trap air, and if in filling these circulating-pipes the water is allowed to flow in both directions from the point of entrance there is a certainty of trapping air at many points. The 85 trouble caused by air in the circulating-pipes is well understood in this art and need not be here dwelt upon.

Heretofore it has been customary to provide each set of circulating-pipes with a pair 90 of cocks, to one of which the device for filling the pipes is attached, the other of said cocks being open to allow the escape of cold air. In the casting comprising these cocks and between the same has been located a butterfly-valve, which can be manually operated to close the passage through the circulating-pipes, so that the water entering through one cock will travel in one direction through the pipes, forcing the air ahead of it and out 100

through the other cock. When the pipes are filled, the cocks are closed and the butterfly-valve is then manually turned so as not to obstruct the passage through the circulating-pipes. The objection due to this construction is the fact that the butterfly-valve must be manually operated and the danger of exploding the circulating-pipes if by any chance the butterfly-valve is not opened after the pipes are filled, for if the passage through the circulating-pipes be closed when the heaters are applied to the system the water will soon be raised to such a temperature that steam will be generated and within a comparatively short time an explosion must ensue. To overcome this objection, I have provided my device which shall automatically close against the incoming current of water when the pipes are being filled, thereby insuring a complete exhaustion of air from the pipes, while at the same time my device will automatically open for the circulation through the pipes of the heated water. I have also provided a simple and convenient means for insuring the attachment of the filling device at the right point.

Referring to Fig. 2, 10 is a casing provided at opposite ends with ports, to which are attached the water-pipes 9 of the circulating system. The casing 10 is also provided with two other ports, to which are attached the nipples A A', leading from the cocks B C. Arranged within the casing 10 and between the ports connecting with the nipples A A' is a valve-seat D. E is a valve arranged to close the valve-seat D. In the preferred construction, as shown in the drawings, the valve E is loosely hung upon an arm F, which is pivoted to the upper part of the casing 10 in such a manner that the valve E will normally hang open; but it is entirely within the spirit of my invention to construct the device so that the valve E shall be normally seated upon the valve-seat D. Arranged within the casing 10 and opposite to the nipple A' is a deflecting-web G. The valve-arm F is loosely swung upon a pin H, which can be mounted within the casing 10, as shown in Fig. 3, and secured in position by means of a plug I, which is threaded into the casing 10 in the manner shown. For the purpose of assembling the parts the casing 10 is provided at one side with a port, which is of sufficient size to admit the valve C D and the valve E and may be permanently closed by means of the plug J. The cocks B C may be conveniently operated by screw-heads K L, which are provided with pointers M to indicate the open and closed positions thereof. Preferably the port connecting with the nipple A is of reduced area, so as to facilitate the filling of the pipes.

It will be understood that it is necessary as the water fills the pipes to exhaust the air from any pockets where it might otherwise be trapped. By providing an outlet of smaller area than the inlet I allow a free escape for 65 the air and also provide for an outflowing current of water of less volume than the inflowing current. Thus the flow of the water fills the pipes and also exhausts the air from all pockets within the pipes, so that the pipes 70 are quickly filled with water and freed from air-pockets. As the filling apparatus usually comprises a nozzle externally screw-threaded, I provide internal screw-threads upon the end of the cock C and external threads upon the 75 cock B, so that the filling apparatus must always be attached to the inlet-cock. Owing to the importance of keeping the circuits closed, in addition to closing the cocks B C when the pipes are filled the cock C is closed 80 by a plug screwed therein and the cock B is closed by a cap N.

While I have shown the preferred form of my device, it will be understood that my invention is not limited to the specific embodiment thereof.

I claim--

1. In a device of the class described, the combination with a casing provided with suitable ports for connection with the pipes of a 90 circulating system, and also provided with a filling-port and a vent-port, the area of the vent-port being less than that of the filling-port, of an automatically-operating valve mounted within said casing and arranged to 95 prevent the passage of water directly through said casing from the filling-port to the vent-port.

2. In a device of the class described, the combination of a casing provided with suitable ports for connection with a system of circulating-pipes and provided with an inlet-port and a vent-port, of an automatically-operating valve mounted in said casing between said inlet-port and said vent-port, and a deflector 100 arranged adjacent to the inlet-port so as to direct the inflowing current of water against said valve in a direction to hold the valve in closed position.

3. The combination with a closed circulating system provided with a normally closed inlet and outlet, connections connecting with said inlet and outlet, respectively, the connection leading to said inlet being provided with means for receiving a fixture not adapted 110 to be so received by the other connection.
